UNITED STATES PATENT OFFICE.

FREDERICK A. ZIEBARTH, OF DELANO, MINNESOTA.

FENCE CONSTRUCTION.

Application filed March 5, 1927. Serial No. 173,169.

This invention relates to fence constructions, and the primary object is to provide a triangularly arranged set of three fence posts, all of which are constructed in a novel, efficient and practical manner, whereby they will be rendered unusually rigid so as to withstand the heavy pull to which they are subjected by virtue of being the anchorage for the fence wires which extend along 10 the edges of the field, frequently for great distances. Further and more specific objects will be disclosed in the course of the following specification, reference being had to the accompanying drawings, in which:

Fig. 1 is a perspective view, partly in section, of a corner of a field, showing the installation therein of my improved fence posts.

Fig. 2 is an elevation of the corner post, 20 a fractional portion being broken away.

Fig. 3 is a sectional detail view on the line 3—3 in Fig. 2.

Fig. 4 is an elevation of one of the side posts.

Fig. 5 is a sectional detail view on the line 5—5 in Fig. 4.

Referring to the drawing more particularly and by reference characters, A, B and C designate the three posts which I employ 30 in each corner, of the field, the same being spaced apart sufficiently far that they may each be, independently and firmly anchored in previously dug post holes. The fence wires D, after being suitably stretched, are 35 primarily secured to the post C, but may also be secured to the posts A and B in the same manner that they are secured to other posts along the edge of the field. While I have shown clamping devices 6, for securing the wires to the post C, it is to be understood that any suitable wire fastening means 40 may be employed. I may also state that while I have here shown my fence posts as made of angle-iron, it may, under certain 45 circumstances, be desirable to use posts of tubular or other forms. The top ends of the posts are firmly and adjustably connected by connecting bars 7, having nuts 8, whereby they will be solidly braced with 50 respect to each other.

The post C is provided, at its lower end, with a link 9, and, at an intermediate point, with a lever 10, which pivots at 11. The outer ends of the members 9 and 10 carry a 55 substantially vertical, T-iron anchor plate 12, the lower end of which has an angularly

projecting lip 13. The inner end of the lever 10 is provided with a plate 14 having a lip 15. The plate 14 has a perforation to receive the lower threaded end of an inclined 60 brace rod 16, having an adjusting nut 17, the upper end of the rod 16 being connected to the upper end of the post, as by a cross pin 18.

The posts A and B are similarly provided 65 with members 9, 12 and 13, but the actuating levers 10^a, in this instance, instead of being substantially straight like the lever 10, are bent levers, and the upright portions are connected to the posts proper by draw 70 bolts 19.

After the post holes have been dug the posts are inserted with the anchor members 12 in their dropped down positions (the bolts 16 and 19 being loose or removed). 75 The plate 14 is now pressed down as far as possible, as with the foot, and the lower end of the rod 16 is inserted in 14, the nut 17 having first been raised as high as possible. The upper end of the rod is now 80 fastened with the pin 18, whereupon the nut 17 is screwed down, thus forcing the plate 12 away from the post and against the solid wall of the hole, and also forcing the lip extensions 13 and 15 into the solid earth. 85 At the limit of the adjustment of the plate 14 should if possible rest on the ground, thus giving further rigidity to the post. The posts A and B are quite similarly rendered 90 very rigid in the ground by drawing up the bolts 19. The tie bars 7 may be applied and adjusted whenever it is found most convenient or desirable to do so.

It will be noted that the posts are now 95 not only rigidly anchored in the ground and with respect to each other, but that each post is anchored directly in contact with the opposite, hard walls of the post hole, and that during the fastening process, the lip extensions 13 have not only become imbedded 100 in the solid ground, but have also, by the lifting effect of the lever action, caused the post proper to more firmly seat itself in the bottom of the hole.

After the posts have thus become properly 105 arranged and adjusted the holes can be filled with dirt, rock or concrete, to keep out water, ice, rodents, etc., as may be found necessary.

It is understood that suitable modifications may be made in the general design and structural details of the invention as herein 110

shown, provided, however, that said modifications come within the spirit and scope of the appended claims.

Having now therefore fully shown and described my invention, what I claim to be new and desire to protect by Letters Patent is:

1. In combination with a fence post, an anchor plate arranged substantially parallel with the lower end of the post and connected therewith by links, and lever acting means for forcibly spreading the anchor plate away from the post.
2. In combination with a fence post, an anchor plate arranged substantially parallel with the lower end of the post and connected therewith by links, and lever acting means for forcibly spreading the anchor plate away from the post, said anchor plate having a projection for engagement in the solid wall of a post hole.
3. The combination with a fence post, of an anchor member connected with the lower portion thereof and adapted to be spread therefrom, a lever acting member for so actuating the anchor member, and means connecting the lever with the post for forcibly actuating the lever.
4. The combination with a fence post, of an anchor member connected with the lower

portion thereof and adapted to be spread therefrom, a lever acting member for so actuating the anchor member, and means connecting the lever with the post for forcibly actuating the lever, said means comprising a threaded bar adjustably connecting the lever with the post.

5. The combination with a fence post, of an anchor member connected with the lower portion thereof and adapted to be spread therefrom, a lever acting member for so actuating the anchor member, and means connecting the lever with the post for forcibly actuating the lever, said lever acting member having a portion for bracing engagement with the ground.

6. The combination with a fence post, of an anchor member connected with the lower portion thereof and adapted to be spread therefrom, a lever acting member for so actuating the anchor member, and means connecting the lever with the post for forcibly actuating the lever, said lever acting member having a portion for bracing engagement with the ground, and said lever also having means for piercing the surface of the ground to effect a maximum bracing of the post.

In testimony whereof I affix my signature.
FREDERICK A. ZIEBARTH.
